(57) CLAIM

The ornamental design for a casino table, as shown and described.

DESCRIPTION

FIG. 1 is a top plan view of a casino table; and, FIG. 2 is an enlarged fragmentary view of the casino table as shown in FIG. 1.

The dash-dot-dot-broken lines enclosing the enlarged partial view in FIG. 2, shown for clarity of disclosure, form no part of the claimed design. The claim comprises the entire top surface of the casino table.
